UNITED STATES PATENT OFFICE.

HATTIE J. PAGE, OF GRAND RAPIDS, MICHIGAN.

GARMENT.

Application filed December 13, 1926. Serial No. 154,534.

This invention relates to garments and more particularly to ladies' dresses or aprons, and its objects are to provide a simply made garment which may be worn with either of its sides used as the front and having certain side extensions made in such a way that they may be either utilized as belts or may be turned inward and used as pockets, and to provide the device with other novel features of construction and arrangement as hereinafter more fully described and particularly pointed out in the claims, reference being had to the accompanying drawings in which,

15 Fig. 1 is a view of the garment laid out flat.

Fig. 2 shows the garment with the side extensions used as belts.

Fig. 3 shows the garment with the side extensions turned inward to be used as pockets.

Fig. 4 shows the garment with side extensions used as a permanently attached belt and also providing pockets, and

25 Fig. 5 is a fragmentary section of the garment illustrating the position of the side extensions when used as pockets.

Like numbers refer to like parts in all of the figures.

30 The garment is preferably made of two similarly cut pieces of material forming the respective sides, either of which may be used as the front or back, these pieces being shaped to form the body portion 1, the neck 2, sleeves 3, and skirt 4. At opposite sides of the body portion near the waist line thereof side extensions 5 are provided. The garment is completed by sewing the two pieces of material together around their outer edges, with the exceptions of the neck and sleeve openings and the bottom of the skirt, this seam following the edges of the side extensions 5.

40 Additional seams 6 are used joining the two members and extending a short distance inward from each side at approximately the waist line just below the side extensions 5 and thence extending downwardly a short distance. These seams 6 come into effect when the side extensions 5 are turned inward as pockets by restricting the diameter of the garment at the waist and thereby making it fit the wearer more neatly.

45 The side extensions 5 may be brought together either at the front or rear of the gar-

ment and fastened by a pin or other suitable means, as shown in Fig. 2, to serve as a belt to gather the garment at the waist, or the extensions 5 may be turned inward and used as pockets, as shown in Figs. 3 and 5. 50 Another use for the extensions is to fold them over the middle of the garment as belts and permanently fasten them in place by sewing along their lower edges and through one thickness of the garment, leaving the upper edges unattached and when so used the members serve as belts and pockets, the pockets being formed between the belts and the body of the garment.

55 A garment made according to this invention is simple and cheap in construction and has many uses. As above described, it may be used as a beltless garment with pockets or the pocket portions may be extended outwardly and folded over to form belts. Owing to the fact that the garment is exactly alike on both sides either side may be used as the front and the belts may be folded over either side of the garment, as desired, and if the proper kind of seam is used to join the two parts of the garment, it may be turned inside out and used equally well in this position.

I claim:

1. A garment comprising two sides each having side extensions near the waist line, said two sides being joined by a seam extending along their edges, and around the edges of the side extensions, and a seam extending from each side of the garment at the approximate waist line, a short distance toward the middle thereof.

2. A garment comprising two sides each having side extensions near the waist line, said two sides being joined by a seam extending along their edges, and around the edges of the side extensions and a seam at each side of the garment at the approximate waist line, each seam extending toward the middle a short distance and thence downwardly a short distance.

3. A garment comprising two substantially similar pieces of material each having side extensions at the approximate waist line, said pieces being joined together by seams extending along their respective edges and around the respective edges of the side extensions.

In testimony whereof I affix my signature.
HATTIE J. PAGE.
